[57] CLAIM

The ornamental design for a jigging lure, as shown and described.

DESCRIPTION

FIG. 1 is a perspective view of a first embodiment of a jigging lure according to the principles of the present invention;

FIG. 2 is a right side elevational view thereof, a left side elevational view not being shown as it is a mirror image of the right side elevational view;

FIG. 3 is a front elevational view thereof;

FIG. 4 is a top plan view thereof;

FIG. 5 is a right side elevation view thereof mounted to a hook;

FIG. 6 is a right side elevational view of a second embodiment of a jigging lure according to the principles of the present invention;

FIG. 7 is a front elevational view thereof;

FIG. 8 is a top plan view thereof;

FIG. 9 is a rear elevational view of the embodiment shown in FIGS. 1-5 and 6-8; and,

FIG. 10 is a bottom plan view of the embodiments shown in FIGS. 1-5 and 6-8.

The broken line showing of a hook is for illustrative purposes only and forms no part of the claimed design.
